FLUID-FLOW INDICATOR FOR AN AQUARIUM FILTER OR THE LIKE

Allan H. Willinger, New Rochelle, and Albert J. Dinnerstein, Brooklyn, N.Y., and Avihu Kagan, Union, N.J., assignors to Metaframe Corporation, Maywood, N.J.

Filed Apr. 10, 1972, Ser. No. 242,899

Term of patent 14 years

Int. Cl. D30—99

U.S. Cl. D30—12

FIG.1

FIG.2

FIG.3

FIG.4

FIG.5

FIG.6

FIG.7

FIG. 1 is a perspective view of a fluid-flow indicator for an aquarium filter or the like showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is an elevational view taken from one side thereof; and

FIG. 7 is an elevational view taken from the side opposite to that shown in FIG. 6.

We claim:

The ornamental design for a fluid-flow indicator for an aquarium filter or the like, substantially as shown.
